US0D1112288S

(12) **United States Design Patent** (10) Patent No.: **US D1,112,288 S**
(45) Date of Patent: ** Feb. 10, 2026

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mani Amini**, Santa Cruz, CA (US); **Jae Woo Chang**, Cupertino, CA (US); **Patrick Lee Coffman**, San Francisco, CA (US); **Thalia Jimena Echevarria Fiol**, Cupertino, CA (US); **Raymond Sepulveda**, Portland, OR (US); **Marcel Van Os**, Santa Cruz, CA (US); **Eric Lance Wilson**, San Jose, CA (US); **Chun Kin Monor Wong**, San Jose, CA (US)

(73) Assignee: **Apple Inc.**, Cupertino, CA (US)

(**) Term: **15 Years**

(21) Appl. No.: **29/953,839**

(22) Filed: **Jul. 24, 2024**

Related U.S. Application Data

(63) Continuation of application No. 29/787,305, filed on Jun. 5, 2021, now Pat. No. Des. 1,040,832.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The outer broken lines in the figures show a display screen or portion thereof, and form no part of the claimed design. The other broken lines in the figures show portions of the graphical user interface that form no part of the claimed design.
